Specification for Design.

Patented Apr. 9, 1912.

Application filed November 21, 1911. Serial No. 661,608. Term of patent 3½ years.

To all whom it may concern:

Be it known that I, JAMES L. LUCAS, a citizen of the United States, residing at Bridgeport, in the county of Fairfield and State of Connecticut, have invented a new, original, and ornamental Design for a Chauffeur's Heel-Rest, of which the following is a specification, reference being had to the accompanying drawing, forming part thereof, in which—

Figure 1 is a plan view of a chauffeur's

heel rest showing my new design, Fig. 2 a side view thereof, and Fig. 3 an end view thereof.

I claim—

The ornamental design for a chauffeur's heel rest, as shown.

JAMES L. LUCAS.
